UNITED STATES PATENT OFFICE.

JESS B. TAYLOR AND CHARLES C. HENNESSY, OF INDIANAPOLIS, INDIANA.

RECORD HOLDER.

Application filed May 15, 1925. Serial No. 30,442.

My invention relates to record holders and has particular relation to record holders for keeping the records of the repairs which are made, or may be made, to railway cars in a 5 yard or station while the cars are in transit.

The general object of our invention is to provide a holder of novel construction which may be readily carried by the person making the repairs, which holder is of a character to 10 hold a supply of record sheets or cards for use and for holding record sheets or cards after they have been written upon.

It is also an object of the invention to provide a box-like holder adapted not only for 15 holding the record sheets or cards, but also to provide a means whereby the writing or making of inscriptions upon the said sheets or cards may be facilitated.

Another object of the invention is to provide 20 a holder having means whereby the removal of a record sheet or card from a supply of record sheets or cards within a compartment of the holder may be facilitated.

A further object of the invention is to provide 25 a box-like holder of novel construction comprising two compartments hingedly connected and adapted to be folded together or to be opened into open position, one of which compartments is adapted to contain a plurality of record sheets or cards ready to be used, while the other of said compartments is adapted to receive and to hold the said cards after they have had notations of 30 repairs and parts furnished inscribed thereon.

In order that our invention may be more 35 readily understood and its practical advantages fully appreciated reference should be had to the accompanying drawing in which we have illustrated certain convenient forms 40 of embodiment therefor. However, it will be understood that changes in the details of construction may be made within the scope of the claims without departing from the invention.

45 In the drawing:

Fig. 1 is a view in perspective of a holder showing the two compartments thereof in extended or open position;

Fig. 2 is a transverse sectional view of the 50 holder with the compartments in open position;

Fig. 3 is a similar view with the compartments in closed position; and

Fig. 4 is a view in perspective of a fragmentary portion of a holder showing a modified construction of means for facilitating the 55

removal of the sheets or cards from the compartment in which the supply of cards is contained.

Referring to the drawing, it will be noted 60 that the holder comprises two box-like members 1 and 2 which are hinged together as shown at 3.

It will be noted that the box-like members 1 and 2 are partially covered by means of 65 plates 4 and 5 which extend in parallel relation to the bottoms of the said members. These plates 4 and 5 are of widths less than the width of the bottoms of the box-like portions or elements 1 and 2 so that openings 6 70 and 7 are provided through which access may be had into the box-like members or elements 1 and 2. The outer edge of the plate or cover 4 is integral with the upper edge of the outer side of the member 1 while the inner edge of 75 the plate 5 is integrally connected with the upper edge of the inner side of the member 2. It follows, therefore, that the opening 6 previously referred to is located adjacent the hinge connection between the two box-like 80 members and that the opening 7 is formed along or adjacent the outer edge portion of the member 2. For the purpose of facilitating the removal of a sheet from the member 2 we have provided an opening 10 in the bottom thereof through which the tip of a finger may be inserted for raising the outer edge 85 portions of the sheets or cards, thereby rendering it easy for a person to grasp the top-most sheet or card and remove the same. 90

Instead of providing a hole 10 as shown we may provide, as illustrated in Fig. 4, a lifting device comprising a lever 11 pivoted at 12 intermediate its ends to the outer side of the member 2. It will be noted that the pivot 95 12 is located very much nearer to one end of the lever 11 than to the other end. The shorter end portion is located near the upper edge of the side of the member 2 to which the lever is pivoted so that it may be pressed inwardly readily to cause swinging movement of the opposite end portion of the lever upwardly or away from the bottom of the member 2 so as to lift the sheets which may be resting upon the inwardly extending projection 13 of the said lever. Either form of construction may be employed as may be preferred, or if desired both means for facilitating the removal of record sheets or cards from the holding member 2 may be embodied 100 in a single structure.

A person inspecting a car and finding that

he must make repairs, the same are made and a record sheet or card is removed from the holding member 2. The holder is then employed or used as a rest and notations are made at once upon the record card or sheet indicating exactly what has been done. These notations having been made the sheet or card is then deposited in the holding member 1 underneath the cover 4.

- 10 We have also provided the holding member 1 with a partition wall 15 spaced from the inner wall or side of the member 1 to form a compartment 16 for holding a pencil or other means for making the necessary notations or 15 inscriptions upon the record sheets or cards. The provision of such pencil holding means constitutes a convenience and its principal purpose is to insure that the person making the inspection shall have always with him a 20 pencil or other notation making means.

Obviously the record sheets or cards which may be placed in the holding members 1 and 2 are relatively narrow.

The record sheet or card holder embodying 25 this invention is of a size which adapts it to be carried in the pocket of a person inspecting railway running gear and cars, and in the use of the same he will remove a record sheet or card from a supply carried in one of the 30 compartments, say the compartment 2, and will note thereon the repairs and replacement of parts made by him; sign his name, and deposit it in the other of the said compartments. Thereafter, for instance at the end of a day, 35 he will remove the cards bearing notations of repairs and replacements and turn them in or forward them to an office for handling in the manner as described in connection with

record sheets disclosed in our applications above referred to and identified. 40

Record sheet or card holding devices embodying our invention facilitate the handling of record sheets and cards for the purpose of making records of repairs.

Having thus described our invention, what 45 we claim and desire to secure by Letters Patent is:

1. A record sheet holder, comprising two rectangular-shaped box-like members which are hinged together at the upper edges of two 50 of their sides, plates for partially covering the said members and connected integrally thereto, and the plate of one of said members being connected to the inner side wall thereof and providing an opening adjoining the outer 55 side wall of the said member.

2. A record sheet holder, comprising two rectangular-shaped box-like members hinged together at the upper edges of their inner 60 side walls, cover plates integrally connected to the said members and partially covering the same, the cover plate of one of said members providing an opening between the inner edge thereof and the inner side wall of said member, and a partition located intermediate the said edge of the said plate for providing a compartment therein, the cover plate of the other of the said members providing an 65 opening between the outer edge thereof and the outer side wall of the said other member. 70

In testimony that we claim the foregoing as our invention we have hereunto signed our names this 11th day of May, 1925.

JESS B. TAYLOR.
CHARLES C. HENNESSY.
